UNITED STATES PATENT OFFICE

2,528,494

MECHANICAL MOBILE TOY

James W. Brookshier, Decatur, Ill., assignor to
 Crown Cork Specialty Corporation, Decatur,
 Ill., a corporation of Illinois

Application September 13, 1949, Serial No. 115,473

6 Claims. (Cl. 46—206)

1

This invention relates to mobile toys, and particularly to toy automobiles which are quite popular with children and are generally made of metal or plastic.

The primary object of the invention is to provide a propelling means for such toys which will be simple and sturdy, easily applied, and will propel the toys at a high rate of speed.

In the accompanying drawing:

Figure 1 is a top view;

Figure 2 is a sectional view;

Figure 3 is a bottom plan view;

Figure 4 is a detail view of the propelling frame; and

Figure 5 is an end view at one end of the propelling frame.

Referring to Figure 1, I have shown for purposes of illustration a toy automobile which is made of either metal or plastic and which has been quite popular with children as a push or pull toy. The invention is applicable, however, to toys of many different designs, as will be appreciated, and I do not wish to be limited to automobiles or similar vehicles.

The numeral 10 designates the body of the automobile and the numeral 11 indicates a propelling frame which is freely and slidably supported by the body. This frame may be formed of a single piece of wire, bent to provide the spaced parallel portions 12, as shown in Figure 4, and looped at its ends to form stop members, as shown at 13, the loops being bent angularly, preferably upward, and being enlarged laterally, as shown at 14. The propelling frame 11 is supported on the body by being slidably disposed in the horizontal slits 15 at each end thereof, the slits being provided intermediate their ends with narrow openings 16 for insertion of the frame. These openings 16 permit insertion of the frame 11 but are sufficiently narrow as shown in order that the frame 11 may be operably confined within the vehicle. The walls of the slits 15 serve to guide the frame in its longitudinal movement with respect to the vehicle body, and in addition, the axle-carrying members 17 connected to the vehicle body also serve to guide the frame in its movement. The parallel members intermediate their ends are connected by a cross member 18 to which is connected one end 19 of a spring 20, the opposite end 21 of which is carried through an opening 22 in the wall of the vehicle, and hooked thereover, as shown at 23 in Figure 2.

In the construction shown, I have illustrated the spring as urging the frame 11 toward the

2

rear of the body, whereby the front loop 13 will engage the same at the front of the vehicle and give the appearance of a bumper, while the rear loop 13 will extend beyond the body, as shown in Figures 1 to 4. With this construction, there is created the normal stressing of the spring 20.

With the construction which has been described, the child places the toy against a fixed object or wall indicated in Figure 1, and moves the vehicle toward the wall against the tension of the spring 20, whereupon release of the fingers from the body 10 will cause the vehicle to move rapidly forward at a fast speed, due to the force of the spring exerted upon the cross bar 18 and the body of the vehicle.

If it is not desired to have the bumper effect at the front, as may be true in the case of some types of toys, the frame 11 may be discontinued at some point within the confines of the body, it merely being necessary to provide suitable guides and a front stop member to limit the outward movement of the frame with respect to the body, and provide for holding the spring under stress.

I claim:

25. 1. A mobile toy constructed for movement in a predetermined direction, said toy comprising a body, a frame supported on said body for sliding movement in said direction, said frame having a stop member on each end thereof to limit the sliding movement of the frame with respect to the body, said stop members cooperating with external portions of the said body, and resilient means connected to the frame and to the body in such a manner that one of said stop members is normally held in engagement with the body under the force of the said resilient means.

2. A mobile toy as set forth in claim 1 wherein said frame is made of a single continuous piece of wire, the ends of which are bent into loops forming the stop members, said loops extending laterally of the body portion of said frame and being bent at substantially right angles to the plane of said frame.

3. A mobile toy constructed for movement in a predetermined direction, said toy comprising a body, a frame supported on said body for sliding movement in said direction, said frame having stop members at its ends, and a spring normally urging one of said stop members in engagement with an external portion of said body, the frame extending outwardly of said body so as to dispose the other stop member at a distance therefrom, said spring being fixed at one end to said body and at the other end to said frame.

4. A mobile toy comprising a body, wheel supporting axles supported by said body, a frame having stop members at its ends slidably supported by said body transversely to said axles and above said axles whereby said axles prevent ready removal of said frame from said body, and a spring normally urging one of said stop members in engagement with said body, the other end of said frame extending outwardly of said body and disposing the other stop member at a distance from the said body, said spring being fixed at one end to said body and at the other end to said frame.

5. A mobile toy comprising a body, a horizontal slit in each end of said body, a frame slidably supported by said body in said slits, said frame having stop members at its ends, and a spring normally urging one of said stop members in engagement with said body, the frame extending outwardly of said body so as to dispose the other stop member at a distance therefrom, said spring being fixed at one end to said body and at the other end to said frame.

6. A mobile toy as set forth in claim 5 wherein narrow openings extending from the edge of said body and intersecting each of said slits are provided for the purpose of assembling said frame in said slits.
